US00D961859S

(12) **United States Design Patent** (10) **Patent No.:** **US D961,859 S**
Tu (45) **Date of Patent:** **** Aug. 23, 2022**

(54) **GRINDING HEAD FOR NAILS**

(71) Applicant: **Zhushi Tu**, Hubei (CN)

(72) Inventor: **Zhushi Tu**, Hubei (CN)

(**) Term: **15 Years**

(21) Appl. No.: **29/687,009**

(22) Filed: **Apr. 10, 2019**

(30) **Foreign Application Priority Data**

Nov. 7, 2018 (CN) 201830626883.6

Primary Examiner — Susan Moon Lee

(57) **CLAIM**

The ornamental design for a grinding head for nails, as shown and described.

DESCRIPTION

FIG. 1 is a front elevational view of a grinding head for nails showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top perspective view thereof; and,

FIG. 8 is a bottom perspective view thereof.

1 Claim, 8 Drawing Sheets
